UNITED STATES PATENT OFFICE.

ROBERT W. LYLE, OF PERTH AMBOY, NEW JERSEY.

BORING-MACHINE.

SPECIFICATION forming part of Letters Patent No. 723,891, dated March 31, 1903.

Application filed June 23, 1902. Serial No. 112,782. (No model.)

To all whom it may concern:

Be it known that I, ROBERT W. LYLE, a citizen of the United States, residing at Perth Amboy, in the county of Middlesex and State 5 of New Jersey, have invented certain new and useful Improvements in Boring-Machines; and I do hereby declare the following to be a full, clear, and exact description of the invention, such as will enable others skilled in 10 the art to which it appertains to make and use the same.

This invention relates to a machine or implement for mortising the ends of underground electrical conduit-sections for the reception of centering or dowel pins.

In the construction of underground electrical conduits consisting of terra-cotta multitudinal sections laid and united end to end it is customary to center said sections relatively to one another by means of dowel-pins or tenons which are fitted in mortises or sockets formed centrally in the ends of the conduit-sections. In such conduits it has heretofore been the usual custom to form circular mortises or sockets in the ends of the conduit-sections at a point where the partitions or webs which form the cells or compartments meet.

In an improved conduit-section invented 30 by me and which will form the subject-matter of a separate application for Letters Patent to be hereinafter filed I form square mortises in the ends of the conduit-sections by cutting away the adjacent or inner ends of 35 the webs or partitions for a suitable depth or distance in such manner as to entirely disconnect or separate such webs and form square sockets for the reception of tenons or dowel-pins square in cross-section.

It is the object of the present invention to 40 provide a machine or implement for cutting such mortises in the ends of the conduit-sections in an accurate, expeditious, and efficient manner; and to this end my invention 45 consists in the features and in the construction, combination, and arrangement of parts hereinafter described, and particularly pointed out in the claims following the description, reference being had to the accompanying 50 drawings, forming a part of this specification, wherein—

Figure 1 is a vertical sectional view of my improved device. Fig. 2 is a bottom plan view thereof. Fig. 3 is a detail perspective view of the auger and chisel. Fig. 4 is a similar view illustrating the guide-blocks, and Fig. 5 is a perspective view illustrating one end of my improved conduit-section.

In Fig. 5 of the drawings I have shown one of the tile-sections for forming my improved 60 underground conduit, each of said sections comprising an earthenware tube *a*, square or rectangular in cross-section and divided into a plurality of longitudinal cells or compartments *b* by cruciform webs or partitions *c*, 65 which extend inwardly from the centers of the sides of the conduit-section to the center thereof, at which latter point said sections are united and form a central core *d*. It is in the ends of such core in which are formed 70 the square mortises *e*, that are designed for the reception of the centering or dowel pins, and, as shown in said Fig. 5 of the drawings, such mortise is formed by removing or cutting away the inner adjacent ends of the 75 webs *c*.

For the purpose of readily, safely, and accurately cutting away the inner adjacent ends of the webs *c* I have invented the mechanism which I will now describe, it only being necessary to preface the description by explaining that the tile or conduit section to be mortised is preferably stood upon end and the mortising-machine applied to the uppermost end thereof and actuated to form the mortise 85 *e* therein.

Referring to Figs. 1 to 4 of the drawings, the numeral 1 indicates the base of the machine, which may conveniently consist of a rectangular frame, which is preferably of approximately the size of the cross-sectional area of the conduit-sections. Attached to the bottom or under side of the base 1 are four depending guide-blocks or lugs 2, said blocks being preferably triangular in shape and having their right-angular sides 3 disposed parallel to one another, as shown, each lug or guide-block being of such size that it will in practice substantially fill one-half of one of the cells or compartments *b* of the conduit-section. The inner or adjacent lower edges of the guide-blocks are beveled, as indicated 95 100

at 2^a; to facilitate their insertion in the cells or compartments of the conduit - sections. Formed centrally in the base 1 is a square aperture 4, the sides of which are parallel 5 with the right-angular sides 3 of the guide-blocks 2, and formed in the adjacent corners of said guide-blocks are vertical right-angular grooves 5, that are in alinement with the corners of the aperture 4. Said grooves 5 10 terminate at their lower ends above the bottoms of the guide-blocks 2, thus forming shoulders 6, for the purpose hereinafter explained.

Attached rigidly to the upper side of the 15 base 1 and straddling the aperture 4 is a U-shaped bracket 7, having firmly fitted between its vertical sides a transverse brace or cross-bar 7^a, said cross-bar and the upper end of the bracket being provided with perforations 8 and 9, in which is rotatably arranged a vertically-movable rod or shaft 10, having formed on or fitted to its lower end an auger or boring-tool 11. The rod or shaft 10 is provided with an annular shoulder 12, on which 20 rests a yoke comprising a perforated disk 13, provided on two of its opposite sides with vertical upwardly-projecting ears or lugs 14, to which are rigidly attached two vertically-dependent arms 15, which carry at their lower 25 ends a hollow square chisel 16, which fits and is vertically movable within the aperture 4 in the base 1 and surrounds the auger 11. A washer 17 is fitted about the rod or shaft 10 and rests on the disk 13, a pin 18 being fitted 30 in a transverse perforation formed in the rod or shaft above the washer and operating, in connection with the shoulder 12, to prevent the chisel from having any vertical movement independently of the auger. As shown 35 in the drawings, the cutting edge of the chisel is arranged slightly below the auger, so as to cut in advance thereof, and thus overcome any liability of the auger chipping, breaking, or cracking the edges of the tile-sections during the operation of the tool.

Arranged around the rod or shaft 10 and resting at its lower end on the cross-bar 7^a is a coiled spring 19, the upper end of which bears against a washer 20, fitted on the rod 40 or shaft beneath the upper end of the bracket 7 and held in place thereon by a pin 21, fitted transversely in the rod or shaft above the washer. The spring 19 operates to normally hold the auger and chisel elevated, and the 45 pin 21 in addition to holding the washer 20 in place also operates as a stop to limit the upward movement of the auger and chisel.

Fitted on the upper end of the rod or shaft 10 is a wheel 22, provided with a crank or 50 handle 23, by means of which the rod or shaft and its attached auger may be rotated.

The operation of my device is as follows: The conduit-section to be mortised is stood upon end, and the guide-blocks 2 are fitted 55 in the cells or compartments b of the tile or conduit section, thereby centering the base

1 on the tile in such manner that the auger rests directly above the end of the core d, and the sides of the chisel 16 respectively lie above the webs or partitions c near the points 70 where the latter join the core d. The operator by means of the wheel or crank 22 rotates the rod or shaft 10 and its attached auger and at the same time forces down the auger against the action of the spring 19. 75 The auger operates to bore a circular hole in the core d, and as the auger is fed down the square hollow chisel is fed down simultaneously with and in advance of it and operates to cut away the inner adjacent ends of the 80 webs or partitions c, and thereby forms a square mortise e centrally in the end of the tile or conduit section. When the cutting edge of the chisel abuts the shoulders 6 at the bottom of the grooves 5, the downward movement of the chisel and auger is arrested, thus gaging the depth to which the mortise is cut. When the wheel is released, the coiled spring 19 raises the auger and chisel and restores 85 them to their normal positions. 90

Having described my invention, what I claim is—

1. In a device for boring holes in the partitions of a tile or conduit section having cellular compartments, the combination with a 95 mortising-tool, of means carried thereby constructed to enter the cellular compartments of a tile and center the mortising-tool over the partition in which the hole is to be bored, and means for operating the mortising-tool. 100

2. In a device of the character described, the combination with a base and a mortising device supported thereon, of guides carried by the base and constructed to be fitted within the cellular compartments of a conduit-section and center the base and mortising device on such section, for the purpose specified. 105

3. In a device of the character described, the combination with a base, and a mortising device supported thereon, of guides on the 110 under side of said base, said guides being arranged to be inserted in the cellular compartments of a conduit-section and embrace the opposite sides of the webs or partitions thereof to center the base and mortising device on 115 such section, for the purpose specified.

4. In a device of the character described, the combination with a base, and a mortising device supported thereon, of guides on the under side of the base, said guides each 120 comprising a substantially triangular block adapted for insertion in one of the cellular compartments of the conduit-section, the said blocks being so disposed as to form a cruciform space between their adjacent edges for 125 the reception of the ends of the transverse webs or partitions of the conduit-sections, for the purpose specified.

5. In a device of the character described, the combination with a base, and a mortising 130 device supported thereon, of guides on the under side of the base, said guides each com-

prising a substantially triangular block adapted for insertion in one of the cellular compartments of the conduit-section, the said blocks being so disposed as to form a cruciform space 5 between their adjacent edges for the reception of the transverse webs or partitions of the conduit-sections, the adjacent edges of the blocks being beveled, for the purpose specified.

6. In a device of the character described, 10 the combination with a centrally-apertured base, and a mortising device supported thereon and movable through said aperture, of guides arranged on the base and adapted for insertion in the ends of the cellular compartments 15 of a conduit-section, said guides operating to center the base and mortising device on such conduit-section, for the purpose specified.

7. In a device of the character described, 20 the combination with a centrally-apertured base, and a mortising device supported on said base and movable vertically through said aperture, of guides arranged on the under side of the base and adapted for insertion in the 25 ends of the cellular compartments of a conduit-section, said guides operating to center the base and mortising device on such conduit-section, and means for projecting the mortising device through the said aperture, 30 for the purpose specified.

8. In a device of the character described, the combination with a centrally-apertured base, and a mortising device supported on said base and movable vertically through said aperture, of guides arranged on the under side 35 of the base and adapted for insertion in the ends of the cellular compartments of a conduit-section, said guides operating to center the base and mortising device on such conduit-section, means for projecting the mortising device through the said aperture, and means for returning the mortising device to its normal position, substantially as described.

9. In a device for boring holes in the intersecting portion of the partitions of a tile or conduit section having cellular compartments, the combination with a mortising-tool, 45 of projections carried thereby constructed to straddle and embrace opposite sides of the 50 said partitions to center the mortising-tool over the intersecting portion of the partitions into which the hole is to be bored.

10. In a device of the character described, the combination with a centrally-apertured 55 base, and guides thereon for centering the base on the end of a conduit-section, of an auger slidably mounted in a bracket carried by the base, a hollow chisel surrounding the auger, means for projecting the auger and 60 chisel through said aperture, and means for rotating the auger, substantially as described.

11. In a device of the character described, 65 the combination with a centrally-apertured base, and guides thereon for centering the base on the end of a conduit-section, of an auger slidably mounted on the base, a hollow

chisel, square in cross-section, surrounding the auger, means for rotating the auger and simultaneously feeding the latter and the chisel through the said aperture, and a spring 70 for returning the auger and chisel to normal position, substantially as described.

12. In a device of the character described, the combination with a centrally-apertured base, and guides on the under side thereof 75 for centering the base on the end of a conduit-section, of an auger, a hollow chisel, square in cross-section, surrounding the auger and suspended on the shank of the latter, means for rotating the auger and simultaneously feeding the latter and the chisel through the said aperture, and a spring for automatically retracting the chisel and auger, substantially as described.

13. In a device of the character described, 80 the combination with a centrally-apertured base, and guides thereon for centering the base on the end of a conduit-section, of a bracket mounted on the base, a rod or shaft rotatably and vertically movable in said 85 bracket, means for projecting said auger and chisel through the said aperture and for rotating the former, and means carried by the guides for limiting the downward movement of the auger and chisel, substantially as de- 90 scribed.

14. In a device of the character described, the combination with an apertured support provided with means on its under side constructed to be fitted into the end of a conduit- 100 section to center the support thereon, of a bracket fixed on said support, a rod or shaft vertically and rotatably movable in said bracket, an auger on the lower end of said rod or shaft, a hollow chisel square in cross- 105 section surrounding the auger and vertically movable with the latter, means for projecting the chisel and auger through the said aperture, and means for rotating the latter, substantially as described.

15. In a device of the character described, the combination with an apertured support constructed to be fitted to the end of a conduit-section, of a bracket fitted on said support and a rod or shaft vertically slidable and 115 rotatably movable in said bracket, an auger on the lower end of said rod or shaft, a hollow chisel, square in cross-section, loosely mounted on but vertically movable with the rod or shaft, means for projecting the chisel 120 and auger through the said aperture, and means for rotating the rod to which the chisel is affixed, substantially as described.

16. In a device of the character described, the combination with an apertured support, 125 constructed to be fitted to the end of a conduit-section, of a bracket fixed to said support, a rod or shaft vertically movable in said bracket, an auger on the lower end of said shaft, a hollow chisel, square in cross-section, 130 loosely mounted on but vertically movable with said rod or shaft, means for projecting

the chisel and auger through the said aperture and for rotating the rod to which the auger is attached, and a spring arranged to return the auger and chisel to normal position, substantially as described.

17. In a device of the character described, the combination with an apertured support, constructed to be fitted to the end of a conduit-section, of a bracket fixed to said support, a rod or shaft vertically movable in said bracket, an auger on the lower end of the shaft, a hollow chisel, square in cross-section, loosely mounted on but vertically movable with the rod or shaft, means for projecting the chisel and auger through the said aperture and for rotating the rod to which the auger is fixed, a spring arranged to return the auger and chisel to normal position, and means for limiting the vertical movement of

the auger and chisel, substantially as described.

18. In a machine for boring holes in the intersecting partitions of a tile or conduit section having cellular compartments, the combination with a base, of a mortising-tool carried by the base, guides on the said base arranged to fit over the end of said tile or conduit section in such manner as to center the mortising-tool over the partition to be bored and hold the base against lateral movement in either direction, and means for operating the mortising-tool.

In testimony whereof I affix my signature in presence of two witnesses.

ROBERT W. LYLE.
